WATER HEATER CONSTRUCTION

Rolland C. Sabins, Wisconsin Rapids, Wis.

Application March 4, 1940, Serial No. 322,081

2 Claims. (Cl. 122—250)

This invention relates to a new and improved water heater and more particularly to heaters of this type in which the heat is supplied by means of an oil burner.

Water heaters as heretofore generally manufactured have comprised comparatively closely wound heating coils interposed in the path of the heating flame. Particularly with pot type oil burners, such a construction interferes with the natural flame pattern and causes deposits of soot or carbon upon the burner structure and upon the colder coil turns adjacent the burner. Coils so located also make it difficult to clean the coils or to reach the burner parts to disassemble the burner and clean it.

It is an object of the present invention to provide a new and improved oil burning hot water heater.

It is a further object to provide such a heater using a pot type burner with the heater parts so located as to maintain the natural flame pattern produced by the pot type burner.

It is also an object to provide a heater in which the water heating coils are so designed as to permit burner parts to be removed for cleaning upwardly through the coils, and to permit cleaning of the coils through an upper opening in the heater.

It is another object to provide a water heater which is simple and compact in design and adapted for commercial production and general household use.

Other and further objects will appear as the description proceeds.

I have shown a preferred embodiment of my invention in the accompanying drawings, in which—

Figure 1 is a vertical section through the water heater, with parts broken away to show the construction;

Figure 2 is a plan view of the heater; and

Figure 3 is a cross-section taken on line 3—3 of Figure 1.

The heater comprises the base member 11 supported by the adjustable feet 12. This base member carries the fuel tank 13 by means of supports 14. The tank 13 has a fuel filling opening 15, below which a usual type of strainer has been indicated at 16. The heater drum 17 is supported on the drum base 18 from the heater base 11. The 50 drum housing 19 surrounds and is spaced from the drum 17 and is supported on the base 11. The annular space 20 between the heater drum 17 and housing 19 is closed at its lower end by the drum base 18 and at its upper end by the cover 55

member 21 having a central opening closed by the removable cover plate 22. The drum base 18 is provided with a central opening 23 for admission of air to the burner.

5 The cross partition 24 is located in the lower portion of the drum 17, this partition supporting the pot type burner 25. This burner is provided with a pilot ring 26, a burner ring 27 and with primary air openings 28, together with secondary air openings 29. The burner itself is of usual construction and its details form no part of the present invention. The fuel pipe 30 leads from the fuel tank 13, flow through the pipe being controlled by the main valve operated by handle 31. 15 This pipe 30 leads to the constant level supply valve 32, the outlet pipe 33 of which is connected to the burner feed pipe 34. This pipe 34 discharges into the pot burner adjacent its bottom in the usual manner.

20 The double water coil 35 is located within the drum 17 above the pot type burner and is connected to a lower intake fitting 36 as well as an outlet fitting 37. These fittings 36 and 37 extend through and are supported by the drum wall 17.

25 It will be noted that the water heating coil 35 is located adjacent the drum wall 17 and is of a greater diameter than the opening in the burner ring 27. It is also of greater diameter than the burner ring 27 itself, so that that ring, as well as the pilot ring 26, may be removed upwardly through the heating coil. This removal

30 can be accomplished through the opening normally covered by the cover plate 22. The heater is provided with the oftake flue 38 which leads from the upper portion of the drum and extends through the space 20. It will be noted that a part of the upper portion of the heating coil 35 extends across the face of the opening in order that the gases passing to the flue may pass

35 directly over and between this section of the heating coils. The dead air space 20 between the heating drum 17 and housing 19 serves to reduce loss of heat and acts as insulation around the heating drum.

40 The entire assembly is simple and compact, and can be constructed commercially and is adapted for general use. Any periodic cleaning of the burner can be readily accomplished by removing the cover 22 and the rings 26 and 27. If required, the heating coils 35 and the interior of the drum can also be cleaned through this opening. The coil 35 is not directly in the flame from the heater but is heated by radiant heat from the flame and from the products of combustion. With the coil located as shown, it is

45

also heated by the heat radiated from the drum walls, which become hot upon continued operation of the apparatus. The placing of the coil out of the path of the flame itself serves to maintain the natural flame pattern produced by a 5 pot type burner and insures efficient operation of the burner. The heating apparatus may be connected in the usual way to a hot water tank and to the source of water supply. The offtake 10 for products of combustion should be connected to a flue to supply draft suitable for a pot type burner.

While I have shown a preferred embodiment of my invention, it is capable of change to meet differing conditions and requirements, and I contemplate such modifications as come within the spirit and scope of the appended claims.

What is claimed is:

1. In a water heater, a vertically extending heating drum, a pot type oil burner in the base of the drum, said burner having a top ring with a 15 restricted central flame opening, a closed parti-

tion supporting the burner from the drum wall, a water heating coil located in the upper portion of the drum concentrically with the burner opening, the coil having a central opening greater in diameter than the burner top ring, and the drum having a removable upper portion whereby the burner ring may be removed through the coil for cleaning the burner.

2. In a water heater, a vertically extending heating drum, a housing surrounding the lateral walls of the drum and spaced therefrom, said housing being joined to the upper end of the drum, a removable cover for the drum, a closed partition in the lower portion of the drum, a pot type burner supported by said partition, said burner having a burner ring with a restricted central opening, and a heating coil fixedly secured in the drum above the partition, said coil having a central opening larger than the burner ring, whereby the burner ring may be removed upwardly through the coil for cleaning the burner.

ROLLAND C. SABINS.
